UNITED STATES PATENT OFFICE.

BENJAMIN HENRY GRIERSON, OF FORT DAVIS, TEXAS.

ATTACHMENT FOR GUN-SLINGS.

1,396,270.

Specification of Letters Patent.

Patented Nov. 8, 1921.

Application filed June 2, 1919. Serial No. 301,287.

To all whom it may concern:

Be it known that I, BENJAMIN HENRY GRIERSON, a citizen of the United States of America, residing in Fort Davis, in the 5 county of Jeff Davis and the State of Texas, have invented a new and useful Attachment for Gun-Slings, of which the following is a specification.

This invention relates to attachments for 10 gun-slings for use on army rifles or other guns; and has for its object to provide means whereby an arm-loop formed on the gun-sling and passing around the muscle of the 15 upper arm may be held tight thereon and prevented from slipping up or down. In this way the gun-sling may be held tight against the arm during aiming, and steady aim thereby facilitated.

Other objects will appear as the nature of 20 the invention is disclosed; and while herein I describe minute details of the attachment, the invention is not limited to these, since many and various changes may be made in structure and arrangement without departing 25 from the scope of the invention as claimed.

In the accompanying drawing, showing by 30 way of example, one of many possible embodiments of my invention,

Figure 1 is a perspective view showing my attachment applied to a gun-sling and in use;

Fig. 2 is a fragmental perspective view, on 35 a larger scale, showing a gun-sling arm-loop with the attachment applied thereto;

Fig. 3 is a side elevation of the gun-sling with attachment applied;

Fig. 4 is a bottom view of the same; and 40 Figs. 5, 6 and 7 are respectively side elevation, bottom view and rear end elevation of the attachment.

The attachment is shown applied to a gun-sling 5 shown secured to a rifle 6 or other gun provided with a butt-swivel 7 and a barrel swivel 8.

The gun-sling comprises a loop-strap or sling-strap 10 passed through said barrel swivel and provided with a double row of 50 perforations 11. The loop-strap is folded upon itself to form at its rear end an arm-loop 15 adapted to receive the muscle of the upper arm of the rifleman as shown in Fig. 1. A hook 16 is riveted to one end of the 55 loop-strap and provided with hook points 17 adapted to engage in said perforations 11.

As stated, said loop-strap is folded upon itself, thereby superposing two thicknesses of the strap on which are disposed the forward and rear slides or runner loops 20 and 21 near said arm loop and barrel swivel respectively, for holding said thicknesses thus superposed.

A metallic link 22 is received on the rear part of the arm loop, and is in turn received by a loop 23 formed on the forward end of the butt-strap 25. The rear portion of the butt-strap is passed through said butt swivel 7 and is provided on its free end with a hook 26 riveted thereto and provided with hook points engaging in the perforations 27 of the butt-strap.

The arm-loop holding attachment 30 is shown in Figs. 5, 6 and 7, and consists of a single piece of wire or rod formed into a frame receiving therein both of the end-members 32 and 33 of the arm-loop, between said loop and the rear runner loop 20. The attachment 30 comprises a yoke portion 34 engaging the exposed face of the inner end-member 32. At the ends of the yoke portion are the side portions 35 engaging both edges of both members 32 and 33 and having their free ends bent inwardly to form inwardly bent portions 36 engaging the outer face of the outer member 33. Joined to said inwardly bent portions are the rearwardly bent spaced parallel portions 38 spaced apart sufficiently for the attachment to be easily slipped onto and from the superposed end-members 32 and 33, said members passing between the spaced portions 38.

The free ends of said spaced portions 38 are bent inwardly and forwardly to form hooks 40 engaging in the perforations 11 to prevent the slipping of said attachment forwardly toward the runner loop 20, thereby preventing the enlarging of the arm-loop, and holding the latter tight on the arm.

In use the attachment and the gun-sling are adjusted as shown in Fig. 1. The attachment may be slipped on before or after the arm has been passed into the arm-loop. It is easily slipped into place over the superposed end-members 32 and 33, the latter passing through the space between the spaced portions 38. After the loop has been properly placed on the arm, the attachment is drawn down until the loop is tight on the arm, and the hooked ends 40 are then hooked into the perforations 11, thereby ef-

fectively preventing the slipping up of the attachment, the enlargement of the arm-loop or the slipping of the latter from proper position on the arm. If desired, the arm-loop 5 may be first tightened by drawing down the runner loop and then fastening the attachment in place. After use, the attachment can be easily slipped from the gun-sling in a manner reverse to the way in which it is 10 slipped on.

Other constructions and uses than those shown, but fully within the scope of the claims, will readily suggest themselves.

I claim as my invention:

15 1. A gun-sling arm-loop attachment comprising a frame adapted without bending to be slipped laterally onto and from two thicknesses of a leather arm-loop, and provided with holding means for positively preventing 20 the slipping of the attachment along the arm-loop while the arm-loop is under tension.

25 2. A gun-sling arm-loop attachment comprising a frame adapted to be slipped laterally onto two thicknesses of a thick leather arm-loop, without springing or distorting the frame or bending the leather, said frame being provided with holding means for positively preventing the slipping of the attachment 30 along the arm-loop while the arm-loop is under tension.

35 3. A gun-sling arm-loop attachment comprising a discontinuous frame adapted, without springing or distortion, to be slipped laterally onto and from two thicknesses of a thick leather arm-loop, and provided with holding means adapted to pass entirely through the leather arm-loop for positively preventing the slipping of the attachment 40 along the arm-loop while the arm-loop is under tension.

45 4. A gun-sling arm-loop attachment comprising a frame adapted to receive two thicknesses of a thick leather arm-loop and comprising spaced portions spaced apart sufficiently to permit said two thicknesses to pass there between without distorting or bending the frame, said spaced portions being provided with hooked ends adapted to 50 engage in perforations in the arm-loop and to pass entirely through the thick leather of the arm-loop.

55 5. A gun-sling arm-loop attachment comprising a frame adapted to receive two thicknesses of a thick leather arm-loop and consisting of a yoke portion, side portions joined to the yoke portion, inwardly turned portions joined to the side portions, and spaced portions spaced apart sufficiently to 60 permit said two thicknesses to pass there between without distorting the frame or bending the leather and provided with hooked ends adapted to engage in perforations in the arm-loop and to pass entirely through 65 the thick leather arm-loop.

6. A gun-sling arm-loop attachment comprising a frame adapted to receive two thicknesses of a thick leather arm-loop and consisting of a yoke portion, side portions joined to the yoke portion, inwardly turned 70 portions joined to the side portions, and spaced portions spaced apart sufficiently to permit said two thicknesses to pass there between without distorting or bending the frame or leather and provided with means 75 for positively preventing the slipping of the attachment along the arm-loop.

7. An attachment adapted to be used with a gun-sling perforated arm-loop having inner and outer loop end-members, said attachment consisting of a single piece of wire folded to form a rectangular frame adapted to receive said end-members and comprising a yoke portion adapted to engage the exposed face of the inner member, side portions adapted to engage both edges of both members, inwardly bent members adapted to engage the outer face of the outer member, and rearwardly extending portions spaced apart as much as the combined thickness of 90 both members, and having forwardly hooked ends adapted to engage in the perforations of the arm-loop and to pass entirely through a leather arm loop.

8. An attachment adapted for use with 95 stiff, thick leather gun-sling arm-loops having an inner loop end member and an outer perforated loop-end member, said attachment consisting of a one-piece wire frame forming a yoke, side portions, inwardly bent 100 portions, and rearwardly extending portions having inwardly and forwardly hooked end-portions adapted to pass entirely through the perforations of the thick leather and to extend forwardly thereof against the inner 105 face thereof, the rearwardly extending portions being sufficiently spaced apart and said inwardly bent portions being sufficiently spaced from said yoke to permit said thick leather loop-end members, when superposed, 110 to be passed between said rearwardly extending members into the frame, without springing or distorting the frame or bending the leather, and to be therein moved to position flat against and parallel to the yoke 115 and inwardly bent members.

9. In combination, a gun-sling having an arm-loop terminating at the arm and engaged tightly around the arm and forming 120 loop end-members; and means adjustably secured on said members for positively preventing the enlarging of the loop while the arm-loop is under tension.

10. In combination, a gun-sling having an arm-loop engaged tightly entirely around 125 the arm and held taut thereby and forming loop end-members, one of which is provided with perforations; and a loop-holding attachment adjustably secured on both of said members and provided with hooks engageable 130

in said perforations for positively preventing the enlarging of the loop when the arm loop is under tension.

11. In combination, a gun-sling having an arm-loop having end-members; a loop holding attachment adjustably positively secured on said members for positively holding the loop against enlargement when the arm loop is under tension; and adjustable means yieldably holding the loop against enlargement while the attachment is being adjusted and secured.

12. In combination, a gun-sling having an arm-loop terminating at the arm and having end-members; a loop holding attachment adapted without distortion to be slipped laterally onto both of said members combined and adjustably positively secured thereto for positively holding the loop against enlargement when the arm loop is under tension.

13. In combination, a gun-sling having an arm-loop terminating at the arm and tightly engaged entirely therearound and provided with perforations and forming loop end-members; a frame-shaped attachment received on said members combined, and provided with spaced hooked ends hooked in said perforations to positively hold the loop against enlargement; and a runner on said end members and serving initially to tighten the arm loop on the arm and to yieldably frictionally temporarily hold the arm loop against enlargement while the hook of the attachment is being inserted in the perforation for the positive holding, by the attachment, of the arm loop against enlargement.

14. In combination, a gun-sling having an arm-loop terminating at the arm and tightly engaged entirely therearound and held taut thereby and forming loop end-members; and a loop holding attachment received on said members and provided with spaced ends spaced apart sufficiently to permit the passage there-between of said members combined.

15. In combination, a gun-sling having an arm-loop terminating at the arm and tightly

engaged entirely there around and held taut thereby and forming loop end-members; and a loop holding attachment received on 50 said members and provided with spaced ends spaced apart sufficiently to permit the passage there between of said members combined; said attachment receiving said members and being adjustably and positively secured on one of said members.

16. In combination, a gun-sling having an arm-loop terminating at the arm and tightly engaged entirely there around and held taut thereby and forming loop end-members; 60 and a loop holding attachment received on said members and provided with spaced ends spaced apart sufficiently to permit the passage there between of said members combined; said attachment being positively secured on said members to positively hold the loop against enlargement.

17. In combination, a gun-sling having an arm-loop terminating at the arm and tightly engaged entirely there around and held taut 70 thereby and provided with perforations and forming loop end-members; and a frame-shaped attachment received on said members combined, and provided spaced hooked ends spaced apart as much as the combined thickness of said members and hooked in said perforations to positively hold the loop against enlargement.

18. In combination, a gun-sling having a sling-strap provided with an arm loop terminating at the arm and forming outer and inner loop end-members provided with perforations; and a loop holding attachment comprising a yoke portion engaging the exposed face of said inner member; side portions; inwardly bent portions engaging the outer face of the outer member; and rearwardly extending spaced portions spaced apart more than the combined thickness of 80 said members and provided with hooked 85 ends engaging in said perforations and positively holding attachment against forward movement and the loop against enlargement.

BENJAMIN HENRY GRIERSON.
